FILM GATE

Application filed March 5, 1930. Serial No. 433,297.

Our invention relates to improvements in cinematographic apparatus and it has particular relation to the film-tensioning means used therein.

5 The tensioning device is usually called a film-gate and consists of an aperture plate and a shoe-carrying plate movable relative to each other and mounted on a supporting plate which, in turn, is rigidly mounted on 10 the main plate of the machine in proper relationship to its other parts.

It is of importance, in mounting these parts, that means be provided for separating the shoe-plate from the aperture-plate with 15 facility to enable the positioning or the removal of the film.

Again, it is essential that, when the gate is in open position, it shall be held rigidly in this position, since an aperture plate or a 20 shoe plate, having a tendency to move during the insertion or the removal of the film, may hamper the operator in his work and thus may cause considerable damage to the film.

Finally, as the film should present a smooth 25 surface to the projection lens and, moreover, as this surface should be at a fixed distance relative to the lens, the gate, when in closed position, must be held rigidly in this position and its parts must not move relative to 30 each other because of the vibration of the machine. A rapid periodic motion of the gate parts results in a periodic fading of the picture on the screen, a phenomenon that is not only disagreeable to the observer but 35 also has a harmful physiological effect upon him.

Film-tensioning means made according to the teachings of the prior art, of which we 40 are aware, may be divided into several classes, with regard to their moving and locking contrivances.

1. Gates equipped with spring-actuated 45 means for clamping the film but lacking any mechanical means for locking their movable parts either open or in closed position.

2. Gates equipped with spring-actuated 50 means for clamping the film, and latch or trigger means for locking their movable parts in open position but lacking means for

locking their movable parts in closed position.

3. Gates equipped with toggle or latch means for locking their movable parts both in open and in closed position. 55

To manipulate successfully the gates of class 1, extraordinary agility is required. Furthermore, the shoe plates of the gates of class 1 and class 2 have a tendency to vibrate with the machine when in closed position. Again, the latch or trigger arrangements of class 2 and the toggle arrangements of class 3 have a tendency to wear rapidly and thus occasion considerable trouble to those manipulating the apparatus. Finally, 65 the toggle locking means is ordinarily complicated in its structure and, hence, a failing in one of its parts may occasion difficulties with the pictures on the screen not easily traceable to the particular part. The confusion resulting from such situation is invariably as costly as it is aggravating. 70

It is, accordingly, an object of our invention to provide a film gate that can be opened with facility and that can be locked rigidly 75 in its open and in its closed position.

A further object of our invention is to provide a film gate that can be manipulated by one not possessed of uncommon agility in handling mechanical apparatus. 80

Still another object of our invention is to provide gate-locking means of simple and inexpensive structure.

Finally, it is an object of our invention to provide a film gate having a structure that 85 readily lends itself to large-quantity manufacturing processes.

According to our invention, we provide dentate means for moving one of the plates of a film-tensioning-device relative to the other, the shaft of one of these plate-moving means being slidably mounted in its bearing, and the supporting bracket of the plate carrying its coacting member being equipped with indentations for holding the end of the 90 slidable shaft of the former at points corresponding to the extreme relative positions of the movable plates of the gate. 95

The novel features that we consider characteristic of our invention are set forth with 1

particularity in the appended claims. The invention, however, both as to its organization and its method of operation, together with additional objects and advantages thereof, will best be understood from the following description of a specific embodiment when read in connection with the accompanying drawing in which;

Fig. 1 is a view, in front elevation, of a specific form of our improved film gate.

Fig. 2 is a sectional view, taken on the line II-II of Fig. 1, and showing, in addition, a number of appurtenances of a motion picture machine in their proper relationship to the film gate.

Fig. 3 is a view, in perspective, of the gate-moving shaft and its parts.

Fig. 4 is a view, in front elevation, of an aperture mask the purpose of which will be described hereinafter.

Fig. 5 is a view, in side elevation, of the aperture mask.

Fig. 6 is a view, in front elevation, of an aperture-mask-locking plate.

Fig. 7 is a view, in side elevation, of the aperture-mask-locking plate.

Fig. 8 is a view, in end elevation, of a part of the machine that will be discussed hereinafter.

Fig. 9 is a view, in rear elevation, of the unit comprising the aperture plate and the supporting plate.

The apparatus shown in the drawing comprises a plate 1 adapted to support the gate, equipped at its corners with a plurality of clearance holes 2 for screws that fasten it to the main plate of the machine and having located, between its horizontal center line and its upper end, a slot 3 and a long bearing-hole 4 through which the levers that actuate a dowser 5, not directly concerned with the present invention, are motivated.

An aperture plate 6, equipped with an aperture 7 that is centrally located below its horizontal center line, is cast integrally with the supporting plate in such a manner as to form substantially a T section therewith. A horizontal groove 8 is cut in the aperture plate 6 in such manner as to completely enclose the aperture, and a plurality of metallic strips 9, adapted to support the margins of the film 10, bridge the groove and are fastened rigidly to the aperture-plate by a plurality of screws 11.

It has been the custom, in the cinematographic art, to provide an aperture mask to give the picture on the screen a rectilinear margin and thus to lend it a neat appearance.

Furthermore, in acoustic-cinematography, a modified form of mask is necessary in order to cover the sound track that would otherwise appear at one margin of the picture, thus presenting a configuration highly distracting to the observer.

By reason of the above requirements, an

aperture-mask 12, an embodiment of which is shown in Figs. 4 and 5, is adapted to be slidably mounted in the slot formed between the groove 8 in the aperture-plate 6 and the strips 9 bridging the groove. The aperture mask is held rigidly in position, when the locking plate 13 is inserted behind it, causing the edges of a raised section 14, which encloses the aperture, to be locked between the edges of the strips.

A plurality of vertical slots 15, located symmetrically near the upper end of the aperture plate, permits the passage of the flanges 16 of a guiding idler, that are rotatably mounted on a shaft 17 supported at its ends by pivots 18 mounted in bearings 19 cast integral with the plate 6.

A plurality of vertical brackets 20, also cast integral with the aperture plate 6, are adjacent to the vertical sides of the aperture 7. The brackets 20 are equipped with vertical tracks 21 to guide the dowser 5, to which reference was made above and, cast integral with them at their upper ends, are a plurality of bearings 22 to support, in a manner permitting longitudinal displacement and rotation about its axis, a shaft 23 that actuates the movable parts of the gate and will now be described in detail.

A knurled knob 24 having a collar 25 integral with it, is rigidly pinned to the shaft 23 at one end, and a pinion 26, also having a collar 27 integral with it, is rigidly pinned near the other end. The pinion 26 meshes with a rack 28 and thus moves, in a horizontal direction, a plate 29 in which the rack 28 is mounted when the knob 24 is turned.

At the extreme end of the shaft 23, adjacent to the pinion 26, is a short section 30, of smaller diameter than the remainder of the shaft 23, that is adapted to ride in a groove 31 in the rack-mounting plate 29 and to enter a plurality of holes 32 located at the ends of the groove 31. To prevent the rack 26 and the pinion 27 from becoming disengaged, and, moreover, to ensure that the tenous end 30 of the shaft 23 shall be held in the holes 32 when it has once entered them, a double end spring catch 33 is rigidly mounted on one of the bearings 22, and coacts with a plurality of notches 34 to lock the shaft 23 against horizontal shifting when the latter are slid directly under either of its ends by the longitudinal motion of the shaft 23.

A wide horizontal slot 35 is substantially centrally located in the gate-supporting plate 1. The slot 35 has a plurality of parallel tracks 36 milled in its vertical boundaries to slidably support the rack-mounting plate 29. A short horizontal slot 37 is cut in the aperture plate 6 in order that the motion of the rack support 29 shall not be obstructed by the plate.

A shoe-carrying plate 38 having a curved section 39 at the top, is mounted on the flange

40 of a ribbed block 41 that is of L section along the center and of rectangular section at the ends and is fastened, by a plurality of screws 42, to the rack mount.

5 In view of the fact that it is essential that the shoe plate 38 and its mountings be movable without effort, one side of the stem of the block 41 is given a smooth machined finish and the block is mounted in such manner that this surface slides in engagement with the machined surfaces of a plurality of bosses 43 of the supporting-plate 1.

10 The shoe-plate 38 is equipped with a rectangular opening 44 that corresponds to the aperture 7 and to a plurality of rectangular slots 45 symmetrically located relative to the opening 44. A plurality of shoe-runner units 46 are loosely mounted in the slots 45 to be resiliently urged in a direction normal to the plates 6 and 38, and hence, normal to the film 15 positioned therebetween, by a multiple end spring 47 rigidly mounted on a block 48 that is integral with the plate 38.

20 In using a motion picture machine, it happens, at times, that the take-up reel does not function and, in order to minimize the fire risk, steps are ordinarily taken to prevent the film from being projected into the path of the light beam between the shoe plate and the objective.

25 In this connection, for the present embodiment of our invention, a flanged tube 49 is provided that is rigidly mounted on the shoe plate 38 to coact with a cylindrical sheet 50 of U-section pivotally supported on one end of an angle bracket 51 that is fastened to the main plate of the machine. The sheet 50 is adapted to be raised to a position wherein it does not obstruct the passage of the shoe-carrying bracket 29 and its appurtenances, and it is, moreover, held in its raised position by the action of a spring catch 53 on a notched plate 54 that is rigidly fastened to the sheet 50. When in its lower position, the sheet 50 forms an enclosure with the main plate of the machine, within which are, respectively, the ends of the tube 49 carried by the shoe plate 38 and the end of the objective mount (not shown) thus, the possibility of the projection of the film strip into the light beam is entirely eliminated.

30 Although we have shown and described certain specific embodiments of our invention, we are fully aware that many modifications thereof are possible. A possible modification of our invention, for example, is the substitution of friction means, for the rack and pinion shown in the present embodiment, as a moving mechanism for the shoe-plate.

35 Our invention, therefore, is not to be restricted except insofar as is necessitated by the prior art and by the spirit of the appended claims.

40 We claim as our invention:

1. Film-tensioning apparatus comprising

45 a supporting plate, an aperture plate rigidly mounted on said supporting plate, a shoe plate movably mounted on said supporting plate, dentate means mounted on said shoe-plate and coacting with dentate means rigidly mounted on said supporting plate to move said shoe plate relative to said aperture plate, and means for locking said shoe plate in one of a plurality of positions.

50 2. In film-tensioning apparatus, means for moving the aperture plate relative to the shoe plate comprising a shaft slidably mounted on said aperture plate, a knob mounted on one terminal of said shaft and dentate means mounted near the other terminal of said shaft, in combination with a support for said shoe plate having rigidly mounted thereon dentate means and having milled therein indentations that coact with means on said shaft to lock said aperture-plate in a plurality of positions.

55 3. In film-tensioning apparatus, a plurality of plates, means for moving one of said plates relative to another comprising a shaft slidably mounted on one of said plates, a knob mounted on one terminal of said shaft, and gripping means mounted near the other terminal of said shaft, in combination with a support for said remaining plate having mounted thereon gripping means and having milled therein indentations that coact with means on said shaft to lock said movable-plate in a plurality of positions.

60 4. A clamping apparatus comprising a casting of T sections, a track milled in the flange of said T section comprising the female of a dovetail, a plate, comprising the male of said dovetail, having mounted thereon a clamping member, dentate means mounted on the stem of said T section coacting with dentate means mounted on the male of said dovetail to move said clamping member relative to said stem of said T section, and means on said male of said dovetail coacting with means in said clamping member to lock said clamping member in a plurality of positions.

65 In testimony whereof, we have hereunto subscribed our names this 23rd day of January, 1930.
